UNITED STATES PATENT OFFICE.

JOHN KIRBY, JR., OF DAYTON, OHIO, ASSIGNOR, BY MESNE ASSIGNMENTS,
TO THE CARTER-CRUME COMPANY.

DESIGN FOR A CASE FOR CASH-REGISTERS.

SPECIFICATION forming part of Design No. 25,012, dated December 24, 1895.

Application filed March 11, 1892. Serial No. 424,589. Term of patent 14 years.

To all whom it may concern:

Be it known that I, JOHN KIRBY, Jr., a citizen of the United States, residing at Dayton, in the county of Montgomery and State of Ohio, have invented and produced a new and original Design for Cash-Register Cases, of which the following is a specification, reference being had to the accompanying drawing forming a part hereof.

The figure is a rear perspective view of the cash-register case, showing my design.

My design consists of a cash-register case, as shown in the drawing.

A is one of the sides or ends, and B the back, of the case. The top E is semicylindrical in shape, as shown.

Having thus described my design, what I claim is—

The design for a cash register case, as herein shown and described.

JOHN KIRBY, JR.
